[57] CLAIM

The ornamental design for a cooking apparatus for toasted sandwiches, as shown and described.

DESCRIPTION

FIG. 1 is a top front perspective view of a cooking apparatus for toasted sandwiches showing the left side of my new design;

FIG. 2 is a front perspective view thereof, the upper platen being in an open condition;

FIG. 3 is a right side perspective view thereof on an enlarged scale;

FIG. 4 is a left side elevational view thereof on an enlarged scale;

FIG. 5 is a bottom plan view thereof on an enlarged scale; and

FIG. 6 is a rear elevational view thereof.
